GRIPPING-LATCH.

1,123,716.

Specification of Letters Patent. Patented Jan. 5, 1915.

Application filed February 2, 1914. Serial No. 815,976.

To all whom it may concern:

Be it known that we, EDWARD ERICKSON and PETER SJOSTROM, subjects, respectively, of the Czar of Russia and the King of Sweden, and residents of Malden, in the county of Middlesex and State of Massachusetts, have invented certain new and useful Improvements in Gripping-Latches, of which the following is a specification.

10 This invention relates to fastenings especially designed for doors, such as automobile doors, although the invention is not limited to such specific use.

One of the objects of the invention is to provide an improved structure of latch which will be noiseless in operation, there being no possibility of any clicking.

Another object is to provide a latch which can be readily released without requiring the expenditure of much strength.

Another object is to provide a device of this character upon which articles of wearing apparel may not become caught.

With this and other objects in view our invention consists in the improvements which we will proceed to describe and claim.

In the accompanying drawings which illustrate our invention in two embodiments, Figure 1 is an elevation of the two members 30 of the latch unsupported by any door or casing structure, the two members being separated to render the illustration clearer; Fig. 2 is a view of the members shown in Fig. 1, looking from above, the two members being connected as when a door is fastened; Fig. 3 represents a section on line 3—3 of Fig. 1; Fig. 4 represents a section on line 4—4 of Fig. 1; Fig. 5 represents a section on line 5—5 of Fig. 1 looking in the 40 direction of the arrows, thereby showing the tongue member in elevation; Fig. 6 represents an elevation of another embodiment of the keeper member; Fig. 7 represents a section on line 7—7 of Fig. 6; and Fig. 8 represents a detail section on line 8—8 of Fig. 6.

Referring first to Figs. 1 to 5 inclusive, in which similar reference characters represent similar parts in all of the views, the 50 casing 12 of the keeper member is provided with a face plate 13 and has a chamber or recess 14 (Fig. 4) which contains most of the mechanism of said member. It is to be understood that the casing 12 is intended

to be fitted in a suitably rabbeted portion 55 of a door casing.

In the particular embodiment of the invention illustrated in Figs. 1 to 5, the device is intended for the door of a automobile, in which case the casing 12 is fitted in a 60 rabbeted portion of the body of the vehicle at one side of the door opening, at such elevation as may be desired, with the operating rod or spindle 27 (which may be of any length) extending up to the top of the door 65 casing. As explained hereinafter, this member might, if desired, be carried by the door instead of by the frame or casing.

One end of the chamber or recess 14 is formed by a wall 15, which is the binding 70 wall, as hereinafter explained, said wall having a curved portion 16 to facilitate the entrance of the tongue hereinafter described.

Mounted in the chamber or recess 14 is a carrier or lever 17, pivoted as at 18, and 75 normally held substantially in the position indicated in Fig. 4, by a suitable spring such as shown at 19. Any suitable portions of the parts may be employed to serve as stops to cause the spring 19 to hold the lever 17, 80 substantially as explained.

The lever 17 is formed or provided with lugs 20 having elongated slots or recesses 21 for a hardened, steel roller binder 22, said roller being loosely mounted for the 85 purpose presently explained.

Between the lugs 20 the end of the lever 17 is formed with an inclined face 23 upon which the roller 22 may roll. The other end of the lever is formed with a heel or rib 90 24 which is engaged by a lug 25 projecting from a collar 26 secured to an operating rod or shaft or spindle 27 mounted in the casing 12, the end of said rod or spindle having a suitable handle 28 whereby the said spindle 95 may be operated to cause the lug 25 to act upon the heel 24 of the lever 17, to shift the latter in a direction which compresses the spring 19, to thereby increase the distance between the roller 22 and the opposite binding wall 15 of the casing.

The casing 29 of the tongue member is adapted to be fitted to a suitably rabbeted portion of a door or a door casing, according to which of these two parts carries the keeper member hereinbefore described. Said casing is formed with projecting portions 30, 31, which act to guard the tongue 32,

the shank 33 of which is mounted to slide in suitably formed ways in the casing 29. The other end of the shank 32 has a lug 34 against which a pin 35, actuated by a spring 36 in a chamber 37 formed in the casing 29, acts to hold the tongue 32 normally in substantially the position shown in Fig. 3, but so that if the door or casing should become warped so that the tongue would not accurately enter the keeper member, the tongue will yield laterally, or in other words, in the direction of the length of its shank, so that the tongue will be properly engaged by the grippers of the keeper member.

In order that the two members will properly come together in case the door should sag somewhat or become raised above its initially placed position, the upper and lower guard members 31 (see Fig. 5) are preferably formed with inclined faces 38.

We employ the terms "tongue" and "keeper" for purposes of explanation only and not with any intent to limit the invention. Either member may be carried by the door and then, of course, the other member would be carried by the door casing. Assuming that the two members shown in Fig. 1 are so mounted that the body of an automobile has the casing 12 secured in a rabbed portion thereof, with the handle 28 above, or perhaps slightly within a cut away portion of the automobile body, and with the casing 29 secured in a suitably rabbed portion of the automobile door. When the door is closed the tongue 32 occupies the position clearly illustrated by dotted lines in Fig. 2, said tongue being slightly, frictionally gripped between the roller binder 22 and the binding wall 15. The spring 19 has a constant tendency to keep the lever or roller carrier 17 in such position that the friction grip will be retained. This is because the angle of inclination of the face 23 is such that the roller 22 is wedged between said face 23 and the outer face of tongue 32, the opposite face of tongue 32 being jammed against the casing wall 15. This grip can be easily released, however, by operating the handle 28 and the spindle 27 so that the lug 25 will operate the heel of the roller carrier or lever to shift the latter in opposition to the spring 19, thus instantly releasing the tongue. After the door has been opened and it has to be again closed, the movement of the parts relatively to each other will be understood by referring to Figs. 3 and 4, such movement being to cause the tongue 32 to enter between the roller 22 and the binding wall 15, which will cause the tongue 32 to rotate easily and practically noiselessly to automatically locked position. In order to secure a positively locked position, it is not necessary that the door should be

closed with a bang. In other words the door need not be caused to fit tightly to its seat, to result in binding or locking of the tongue 32. This is because the tongue 32 will be locked regardless of whatever portion of its length is gripped between the roller 22 and the binding wall 15.

Referring now to Figs. 6, 7 and 8, the casing 41 of the keeper member has a face plate 42 and is provided with a chamber or recess 43, one wall of which presents a binding surface at 44. In the chamber or recess is mounted a carrier or lever 45, pivoted as at 46, and held in normal position by a spring 47. One end of the pivoted carrier or lever 45 is provided with lugs 48 having elongated recesses or slots 49 which loosely support the roller binder 50 in juxtaposition to the inclined face 51 of the lever 45. The other end of the lever 45 carries a roll 52, which is actuated by a cam 53, carried by a spindle 54, mounted in the casing 41 and having a suitable handle or knob 55. This form of device is more suitable for ordinary doors in buildings. The cam 53 is provided with a radial ear 61 carrying a pin 56 which passes through an arc slot 47 in the casing into the path of a pin 58 (Fig. 8) mounted in a chamber 59 in the casing, and held against the pin 56 by a spring 60 in said chamber.

With this structure of keeper member just described, a tongue member similar to that illustrated in Fig. 3 will be employed, the only difference being that the casing of the tongue member must be so constructed as not to interfere with the casing of the keeper member. The operation of the binding roller and its pivoted carrier shown in Figs. 6 and 7 is, of course, the same as that employed in the first structure described. The spring 60 serves to normally hold the knob or handle 55 in its inactive position, with the cam so located as not to interfere with the lever 45 remaining in position to cause the roller binder 50 to automatically grip a tongue member that is inserted between the roller 50 and the binding wall 44. By rotating the knob, however, in a direction to compress the spring 60, the cam 53 acts upon the lever 45 to swing the latter and increase the space between the roller 50 and the wall 44, so as to release the tongue member that has been gripped therebetween.

What we claim is:

1. A device of the character described, comprising a tongue member, and a keeper member provided with co-operating grippers to clamp the tongue member, one of said grippers being pivotally mounted and extending from its pivot in a direction nearly at a right angle to one side of the tongue member to exert a direct thrust against said side of the tongue member to resist withdrawal of the latter.

2. A door catch comprising two members one of which has inelastic relatively movable frictional grippers, the other having a projecting member provided with longitudinally extended faces to be clamped by said grippers.
3. A door catch comprising two members one of which has frictional grippers, the other having a projection to be engaged by said grippers, and guard devices to prevent said projection from catching clothing.
4. A door catch comprising a tongue member and a keeper member, the keeper member having a movable roller and a fixed wall spaced from the roller to admit the tongue member, said roller being movable in a direction to grip the tongue member with a wedging action.
5. A door catch comprising a keeper member having a fixed wall and a movable carrier having a roller spaced from said wall, and a tongue member to be gripped between said roller and wall.
6. A door catch comprising a keeper member having a fixed wall and a pivotally supported carrier having an inclined face opposite said wall, said carrier having a loosely mounted roller, and a tongue member to be gripped between said roller and wall.
7. A door catch comprising a keeper member having grippers, and a co-operating member having a tongue to be engaged by said grippers, the tongue being yieldingly movable laterally.
8. A device of the character described, having a tongue member provided with substantially flat parallel faces, and a keeper member having a fixed jaw and a relatively movable jaw to frictionally grip said faces of the tongue member in any position lengthwise of the tongue member.

In testimony whereof we have affixed our signatures, in presence of two witnesses.

EDWARD ERICKSON.
PETER SJOSTROM.
